UNITED STATES PATENT OFFICE

143,501

DESIGN FOR A PIANO

Charles C. Nields, Los Angeles, Calif.

Application August 7, 1945, Serial No. 121,299

Term of patent 7 years

(Cl. D56—9)

To all whom it may concern:

Be it known that I, Charles C. Nields, a citizen of the United States, residing at Los Angeles, in the county of Los Angeles and State of California, have invented a new, original, and ornamental Design for a Piano, of which the following is a specification, reference being had to the accompanying drawing, forming part thereof.

The drawing illustrates a piano embodying my new design in which Fig. 1 is a perspective view, and Fig. 2 is an end elevational view.

I claim:

The ornamental design for a piano, as shown.

CHARLES C. NIELDS.
